(57) **CLAIM**

The ornamental design for a mobile phone case, as shown and described.

DESCRIPTION

FIG. 1 is a perspective view showing our new design for a mobile phone case;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective illustrating the mobile phone case of the present invention in its environment of use.

The broken lines in the drawings depict unclaimed portions of the case only and form no part of the claim designed.

1 Claim, 7 Drawing Sheets
